UNITED STATES PATENT OFFICE.

FREDERIC E. YOUNG, OF SHREVEPORT, LOUISIANA.

BARBER'S CLIPPER GUARD.

Application filed June 7, 1923. Serial No. 643,988.

This invention relates to hair clippers and more particularly to guards therefor.

By way of explanation it may be said that barber's clippers are marked 0—00—000 and #1 and the object of the invention is to provide a guard for clippers of this character so constructed as to facilitate the tapering or feather edging of the hair starting with triple naught (000) work and going into double naught (00) then into naught (0) and from that into one (1) and longer where the comb work begins all of which are accomplished in a single operation, using the rolling motion with the clippers without leaving any line of demarkation in passing from one length to the other and by means of which the work of four clippers may be accomplished with the use of one.

Another object is to provide a clipper guard so constructed and mounted that all kinds of hair will be picked up and guided into the cutting teeth no matter how fine the hair may be and which will also pick up hair from the scalp which rolls up in front of the clipper and which will slide easily and without sticking to the skin.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed without departing from the spirit of the invention.

In the accompanying drawings:—

Figure 1 represents a side elevation of a hair clipper with this improved guard shown applied.

Fig. 2 is a top plan view of the guard detached.

Fig. 3 is a bottom plan view thereof.

Fig. 4 is a longitudinal section taken on the line 4—4 of Fig. 2; and

Fig. 5 is a transverse section taken on the line 5—5 of Fig. 2.

Referring in detail to the drawings, where in like characters of reference denote corresponding parts, the clipper which is designated in its entirety by the reference char-

acter 1 includes a base plate 2 of usual construction which carries at its front end stationary teeth 3 which cooperate with movable teeth 4 to effect the cutting operation. 55

The guard 10 constituting this invention comprises what may be termed a taper plate of brass or other suitable metal shaped as shown in Figs. 2 to 5 having a flat inner face 11 and upturned teeth 12 at its front edge. 60 The lower face of said plate being rounded transversely as shown at 13 and preferably corrugated transversely as shown at 14 to prevent the plate from sticking to the flesh. Extending longitudinally of the inner face 65 of the plate 10 is a recess 15 having undercut side walls 16 and in which is mounted an attaching plate 17 which fits tightly in said recess and is secured frictionally by the undercut side walls. This plate 17 which is 70 designed for adjustably connecting the guard to the clipper base plate 2 has upwardly and inwardly inclined ends which fit closely around the ends of the clipper base plate as is shown clearly in Fig. 1 and which hold the 75 guard in operative position on the clipper permitting it to be slid backward or forward according to the length it is desired to cut the hair.

The peculiar construction of this guard 80 or taper plate 10 adapts it to be used on a full width clipper finer than #1 and its use on a triple naught clipper by adjusting it backwards or forwards enables an operator to produce a gradual taper of the hair from 85 one-sixty-fourth to one-fourth of an inch without leaving any lines of demarkation thus enabling a man to do the work of four clippers by the use of one only. Moreover 90 by moving the guard 10 forward so that the teeth 12 thereof project beyond the ends of the cutting teeth of the clipper finest kind of hair will be picked up and guided to the cutting teeth and no matter how the scalp rolls in front of the clipper with the teeth 95 of the guard projected the clipper can cut only a length equal to the distance between the bottom of the plate and the cutting teeth of the clipper.

Various changes in the form, shape, proportion and other minor details of construction may be made without departing from 100

the principle or sacrificing any of the advantages of the claimed invention.

I claim:—

A clipper guard embodying a plate having upwardly curved teeth formed along one edge thereof, the under surface of the plate being rounded at the junction of said teeth with the plate, the lower surface tapering

towards the rear edge thereof, said plate having grooves formed transversely thereof, 10 said grooves extending to points between the teeth, and means for securing the plate directly to a clipper.

In testimony that I claim the foregoing as my own, I have hereto affixed my signature.

FREDERIC E. YOUNG.
